DESIGN FOR A BRASSIÈRE OR SIMILAR ARTICLE

George A. Kaufmann, Essex Fells, N. J., assignor to The H & W Company, Inc., Newark, N. J., a corporation of New Jersey

Application July 1, 1937, Serial No. 70,198

Term of patent 7 years

To all whom it may concern:

Be it known that I, George A. Kaufmann, a citizen of the United States, residing at Essex Fells, county of Essex, State of New Jersey, have invented a new, original, and ornamental Design for a Brassière or Similar Article, of which the following is a specification, reference being had to the accompanying drawing, forming a part thereof.

Fig. 1 is a perspective view of a brassière showing my new design; and

Fig. 2 is a front elevation of the same.

I claim:

The ornamental design for a brassière or similar article, as shown.

GEO. A. KAUFMANN.
